UNITED STATES PATENT OFFICE.

CHARLES J. BARNETT, OF NEODESHA, KANSAS.

MACHINE FOR ROUGHENING CLAY RIBBON.

1,221,014.

Specification of Letters Patent.

Patented Apr. 3, 1917.

Application filed March 10, 1916. Serial No. 83,358.

To all whom it may concern:

Be it known that I, CHARLES J. BARNETT, a citizen of the United States, residing at Neodesha, in the county of Wilson and State 5 of Kansas, have invented certain new and useful Improvements in Machines for Roughening Clay Ribbon, of which the following is a specification.

My invention relates to improvements in 10 brick machines of that class which employ the stiff-mud process, wherein a clay-ribbon is produced and is cut into brick sizes, ready for the kiln; and has particular reference to means for matting or roughening the surface 15 or surfaces of the ribbon preferably prior to the cutting thereof, whereby the surface or surfaces of the brick will have a peculiar heavy rough appearance.

An important object of the invention is to 20 provide a machine of the above mentioned character, which is adapted to operate in a highly expeditious manner.

A further object of the invention is to provide such a machine, which is adjustable to 25 act upon different sizes of ribbons.

Other objects and advantages of the invention will be apparent during the course of the following description.

In the accompanying drawings forming a 30 part of this specification and in which like numerals are employed to designate like parts throughout the same,

Figure 1 is a front side elevation of the machine embodying the invention,

Fig. 2 is a plan view of the same,

Fig. 3 is a side elevation of the machine, and,

Fig. 4 is a vertical sectional view taken on line 4—4 of Fig. 1.

In the drawings, wherein for the purpose of illustration is shown a preferred embodiment of my invention, the stationary frame of the machine is shown as comprising vertical beams 10, having flanges 11. These 40 beams are held stationary by any suitable means and are arranged near a brick machine 12, having a discharge chute 13 connected therewith and projecting between the beams 10. The clay-ribbon is discharged 45 from the machine 12 through the chute 13, in the direction of the arrow.

Bolted or otherwise attached to the rear flanges 11 of the beams 10 are strips 14, extending above the beams 10 and having

bearings 15, arranged thereon. These bearings are secured in place by bolts 16, operating through elongated slots 17, whereby the bearings 15 are vertically adjustable. Journaled through the bearings 15 is a horizontal driving shaft 18, upon one end of which is 60 rigidly mounted a pulley 19, receiving power from any suitable source.

The numeral 20 designates a reel, comprising end disks or heads 21, having hubs 22. These hubs are preferably longitudinally 65 adjustably mounted upon the shaft 18 and are clamped thereto by bolts 23 or the like. The disks 21 are connected by preferably cylindrical rods 24, as shown. These rods have connection between their ends with an 70 interior reinforcing ring 26, serving to prevent them bending inwardly, but it is to be understood that this ring may be omitted, if desired, and the rods 24 formed suitably stiffer.

Rigidly mounted upon the opposite end 75 of the shaft 18 is a sprocket wheel 27, engaged by a sprocket chain 28, extending downwardly to engage a sprocket wheel 29, rigidly mounted upon the corresponding end 80 of a lower horizontal shaft 30. This lower shaft 30 is journaled through vertically adjustable bearings 31, contacting with the outer sides of the forward flanges 11, and secured thereto by bolts 32, operating in 85 elongated slots 33, in the flanges. The shaft 30 has beveled gears 34 rigidly mounted thereon, engaging bevel gears 35, rigidly attached to the lower ends of vertical shafts 36. The lower portions of these shafts 36 90 are journaled in bearings 37, which are arranged upon a horizontal strip 38. The bearings 37 are secured thereto by bolts 39, operating in elongated slots 40 formed in the horizontal strip 38 whereby the bearings 95 37 are horizontally adjustable. The strip 38 has upwardly extending laterally off-set arms 41, arranged in contact with the flanges 11. The arms 41 have elongated slots 42, receiving bolts 43, carried by the flanges 100 11. It is thus apparent that the strip 38 is vertically adjustable. The upper portions of the shafts 36 are journaled through bearings 44, which contact with an upper strip 45, having depending arms 46. The arms 105 46 are provided with longitudinal slots, receiving bolts 47, whereby the horizontal strip 45 is vertically adjustable. The horizontal

strip 45 is provided with elongated slots 48, receiving bolts 49, carried by the bearings 44. It is thus apparent that the bearings 44 may be longitudinally adjusted upon the strip 45. Rigidly mounted upon the shafts 36 are reels 50, substantially identical with the reel 20 and comprising disks 51 connected by rods 52. Attention is called to the fact that the reels 50 are preferably disposed at a right angle to the reel 20 and beneath the same. The reels 50 are disposed near and upon opposite sides of the chute 13 to contact with the opposite sides of the clay-ribbon passing through the chute 13.

10 In the operation of the machine, the clay-ribbon is fed through the chute 13 in the direction of the arrow, while the pulley 19 is driven in the direction of its arrow or counter-clockwise. The upper horizontal reel 20 is therefore rotated in the same direction, in contact with the upper side of the brick ribbon. The gearing between the shaft 18 and the side reels 50, is such that the latter rotate in the opposite direction to 20 the travel of the clay-ribbon and contact with the sides thereof. The reels are rotated at a high speed, preferably 180 revolutions per minute, and by traveling in contact with the clay-ribbon and in the opposite direction thereto, impart to the clay ribbon a peculiar heavy rough appearance. After being treated by the action of the 30 reels, the clay-ribbon is conducted to a cutting machine, and formed into bricks, as is customary.

35 It is to be understood that the form of my invention herewith shown and described is to be taken as a preferred example of the same, and that various changes in the shape, size, and arrangement of parts may be resorted to without departing from the spirit 40 of the invention or the scope of the subjoined claim.

Having thus described the invention, I claim:

45 In a machine of the character described; a pair of upstanding beams; vertically adjustable bearings arranged upon the rear side of the beams near their upper ends; means for connecting the bearings with the 50 beams; a substantially horizontal shaft journaled through the vertically adjustable bearings; a substantially horizontal reel carried by the shaft; a pulley secured to the shaft to drive it; a substantially horizontal upper 55 strip secured to the forward side of the beams near their upper ends; bearings secured to the upper strip and adapted to be horizontally adjusted thereon; a substantially horizontal lower strip having upstanding extensions which are adjustably connected with the forward sides of the beams so that the lower strip may be raised and lowered; bearings carried by the lower strip and adapted to be adjusted horizontally 60 thereon; substantially vertical spaced shafts journaled in the bearings carried by the upper and lower strips whereby said substantially vertical shafts are adjustable toward and away from each other; substantially vertical reels carried by the substantially vertical shafts; gears carried by the lower ends of the substantially vertical shafts; coacting gears; a lower substantially horizontal shaft carrying the co-acting 75 gears; vertically adjustable bearings receiving the lower shaft and connected with the forward side of the beams; and gearing between corresponding ends of the upper and lower shafts.

65 70 75 80 In testimony whereof I affix my signature in presence of two witnesses.

CHARLES J. BARNETT.

Witnesses:

J. W. BOGUE,
J. T. FLOYD.
